ACCORDION

Ermoly Demianenko, New York, N. Y.

Application March 18, 1937, Serial No. 131,621

4 Claims. (Cl. 84—376)

This invention relates to accordions, and particularly to piano type accordions, wherein the tonal reed valves are operated by banks of keys akin to the regular piano keyboard, the bank of 5 white keys operating the major scale valves and the black keys operating the minor scale valves. In such piano accordion it is possible to play a fast run of successive major scale tones by running the fingers pressingly and without striking 10 over the bank of white keys from left to right, but it is not possible to similarly play a run of chromatic scale tones, for the reason that the black minor keys are situated rearwardly and are disposed in elevated protrusion above the 15 white keys.

The principal object of the invention is to provide a piano accordion with means wherewith the musician may be enabled to play a run of chromatic scale tones as conveniently and efficiently as it was heretofore possible to play a fast run of major scale tones on such instrument.

Other objects and advantages will hereinafter appear.

25 In the accompanying drawing,—

Fig. 1 is a perspective view showing a fragmentary portion of a piano accordion equipped with the improvements of this invention.

Fig. 2 is a transverse-sectional side elevation 30 of a piano accordion of the invention.

The accordion 1 comprises bellows 2, a partition 3, a set of reed boxes 4 with reeds 5 for the major scale tones carried by said partition, a set 35 of reed boxes 6 with reeds 7 for the minor scale tones similarly carried by the partition, outlets 8 in partition 3 for said boxes, valves 9, 10, for said outlets, a bank of white piano keys 11 fulcrumed at 12 in a framing 13 for operating the valves 9, and a bank of black keys 14, similarly fulcrumed at 15 for operating the valves 10. Each 40 of the white keys 11 operates its valve 9 by an arm 16 thereof being joined to said valve, and each of the black keys 15 similarly operates its valve 10 by an arm 17 thereof being joined to the latter. Springs 18 bearing upon said keys 45 and the framing 13 press the keys 11, 14 upwardly to normally maintain the valves 9, 10 in the closed state shown, while pressing downwardly upon said keys opens the valves for production 50 of the tones.

Underneath the banks of keys 11, 14 is located a series of plunger rods 19 mounted and longitudinally slidable in guiding bearings 20 depending from the framing 13. Each rod 19 is provided at its forward terminal with a finger-piece

21 constituting a playing key, and carries at its opposite terminal a flange 22, collars 23 secured to rod 19 normally abutting against the bearings 20 to limit the outward movement of the rod as viewed in the drawing. For each of the plungers 5 19 there is provided a lever 24 fulcrumed at 25 to a post 26 fixed to partition 3. The forward terminal 27 of lever 24 abuts against the plunger-flange 22, while its opposite terminal 28 abuts either against an arm 17 of a valve 10 or an arm 10 16 of a valve 9, according to whether conjoint operation is required from key 21 of a valve 10 or a valve 9, the finger pressure upon said key in this manner causing its rod 19 and flange 22 to swing the lever 24, and to press upwardly upon 15 arm 17 or 16 to open its corresponding valve 10 or 9.

There is thus provided a key 21, with its above described operating parts 19, 24, for each of the white keys 11 of the major scale as well as for 20 each of the black keys 14 of the minor scale, and the keys 21 are arranged successively in the chromatic scale order, in convenient relation to the musician's fingers, as illustrated in Fig. 1. The musician is therefore enabled to run his 25 fingers pressingly and without striking over this third bank of keys 21, toward the right or toward the left, and thereby perform a fast run of chromatic scale tones, for producing desired musical effects.

30 Variations may be resorted to within the scope of the invention.

Having thus described my invention, I claim:

1. An accordion having the combination of a set of major scale reeds, a set of minor scale 35 reeds, valves for said reeds, a bank of piano keys for said major scale reed valves, another bank of piano keys for said minor scale reed valves, a bar joining each of said keys with its respective valve, a longitudinally movable plunger rod for 40 each of said keys located underneath it and parallel thereto, said rod being mounted in guiding means therefor, the operative forward terminal of said rod carrying a finger piece located at the forward terminal of its related major scale key, 45 said finger pieces being arranged in chromatic scale order, and means to transmit the movement of said rod to the bar of its respective key.

2. An accordion having the combination of a set of major scale reeds, a set of minor scale 50 reeds, valves for said reeds, a bank of piano keys for said major scale reed valves, another bank of piano keys for said minor scale reed valves, a bar joining each of said keys with its respective valve, a longitudinally movable plunger rod un- 55

- derneath each of said keys and disposed parallel thereto, means for mounting and guiding said rod, a finger piece carried by the operative forward terminal of said rod being situated at the 5 frontal terminal of its related major scale key, said finger pieces being arranged in chromatic scale order, and a lever transmitting the movement of each of said rods to the bar of its respective key.
- 10 3. An accordion having the combination of a set of major scale reeds, a set of minor scale reeds, valves for said reeds, a bank of piano keys for said major scale reed valves, another bank of piano keys for said minor scale reed valves, 15 means joining each of said keys with its respective valve, a longitudinally movable plunger rod underneath each of said keys disposed parallel thereto, means for mounting and guiding said rod, a finger piece carried by the operative frontal 20 terminal of said rod being disposed at the frontal

terminal of its related major scale key, said rods and finger pieces being arranged in chromatic scale order, and means transmitting the movement of each of said rods to its respective valve.

4. An accordion having the combination of a set of major scale reeds, a set of minor scale reeds, valves for said reeds, a bank of piano keys for said major scale reed valves, another bank of piano keys for said minor scale reed valves, means joining each of said keys with its respective valve, a longitudinally movable plunger rod underneath each of said keys disposed parallel thereto, means for mounting and guiding said rod, the operative frontal terminal of said rod being disposed at the frontal terminal of its related major scale key, said rods being arranged in chromatic scale order, and means transmitting the movement of each of said rods to its 15 respective valve.

ERMOLY DEMIANENKO. 20
